UNITED STATES PATENT OFFICE.

HENRY F. MCKNIGHT, OF INGRAHAM, ILLINOIS, ASSIGNOR OF TWO-THIRDS TO
JOSEPH L. MCKNIGHT AND WESLEY E. JACKSON, BOTH OF SAME PLACE.

THILL-CO尤LING.

SPECIFICATION forming part of Letters Patent No. 432,064, dated July 15, 1890.

Application filed May 2, 1890. Serial No. 350,345. (No model.)

To all whom it may concern:

Be it known that I, HENRY F. MCKNIGHT, a citizen of the United States, residing at Ingraham, in the county of Clay and State of Illinois, have invented a new and useful Thill-Coupling, of which the following is a specification.

The invention relates to improvements in thill-couplings and anti-rattlers.

10 The object of the present invention is to provide a simple and inexpensive thill-coupling which is capable of ready adjustment to different-sized thill-irons, and in which the wear can be readily taken up, and which will prevent noise and rattling and dispense with springs and rubbers usually employed to accomplish this result.

15 The invention consists in the construction and novel combination and arrangement of parts, hereinafter described, illustrated in the accompanying drawings, and pointed out in the claims hereto appended.

20 In the drawings, Figure 1 is a perspective view of a thill-coupling constructed in accordance with this invention. Fig. 2 is a vertical transverse sectional view. Fig. 3 is a horizontal sectional view. Fig. 4 is a detail view of the clip. Fig. 5 is a similar view of one of the bearing-blocks.

25 Referring to the accompanying drawings, 1 designates an axle-clip of the ordinary construction, provided at its front end with a laterally-projecting plate 2, formed integral with the clip, and provided with a countersunk slot 3 and a countersunk opening 4, arranged upon opposite sides of the clip-arm to receive bolts 5 and 6 to secure it to the clip bearing-blocks 7. The countersunk slot 3 enables the bolt and its bearing-block to be adjusted laterally to adapt the coupling to any-sized thill-iron, and the bolt 6 may, if desired, be formed integral with the plate of the clip; but it is found preferable to construct it as illustrated in the accompanying drawings.

30 The bearing-blocks 3 are provided with horizontal holes 4, through which pass the bolts 5 and 6, the outer ends of which are threaded and adapted to receive nuts 8, to secure the

bearing-blocks, and the rear ends of the latter fit squarely against the plate 2 of the clip. 50 The bolts 5 and 6 are parallel and are arranged in the same horizontal plane, and the bearing-blocks 7 are oppositely disposed and are provided with bearing-openings 9, having their inner opposite edges countersunk and 55 adapted to receive oppositely-beveled ends 10 of the eye 11 of a shaft or thill iron 12, and thereby provide cone-bearings. The said iron 12 is secured between the bearing-blocks by a coupling-bolt 13, having a squared head 60 14, and the threaded end of the bolt receives a nut 15, by which the parts may be readily tightened to take up wear and prevent noise and rattling and to regulate the adjustment of the laterally-sliding bolt. 65

It will readily be seen that the thill-coupling and anti-rattler is simple and inexpensive in construction and is adapted to take up the wear of the parts and dispenses with the springs, rubbers, and the like usually 70 employed in an anti-rattler.

What I claim is—

1. In a thill-coupling, the combination of the clip, the bolts projecting forwardly therefrom and arranged at each side of the same, 75 the bearing-blocks secured upon the bolts and provided with bearing-openings, and the thill-iron arranged between the bearing-blocks and secured thereto by a coupling-bolt, substantially as described. 80

2. In a thill-coupling, the combination of the clip having the integral plate 2, provided with bolt-openings, the bolts arranged in said openings and projecting forwardly from the clip, the bearing-blocks provided with horizontal openings to receive the bolts and having countersunk bearing-openings, the thill-iron having its eye oppositely beveled and arranged in the countersunk bearing-opening, and the coupling-bolt, substantially as 85 described. 90

3. In a thill-coupling, the combination of the clip having the plate 2 formed integral therewith, and provided with the countersunk slot 3 and the countersunk opening 4, the 95 bolts 5 and 6, arranged in the slot and the

opening, the bearing-block fitting squarely against the plate 2 and provided with horizontal holes 4 to receive the bolts, and having countersunk bearing-openings, the thill-
5 iron having its eye oppositely beveled, and the coupling-bolt, substantially as described.

In testimony that I claim the foregoing as

my own I have hereto affixed my signature in presence of two witnesses.

HENRY F. McKNIGHT.
